UNITED STATES PATENT OFFICE.

WALTER C. BECKWITH, OF FOSTORIA, OHIO.

TUBE-MAKING MACHINE.

SPECIFICATION forming part of Letters Patent No. 659,567, dated October 9, 1900.

Application filed February 20, 1899. Serial No. 706,190. (No model.)

To all whom it may concern:

Be it known that I, WALTER C. BECKWITH, a citizen of the United States, residing at Fostoria, in the county of Seneca and State 5 of Ohio, have invented new and useful Improvements in Tube-Making Machines, of which the following is a specification.

My invention relates to improvements in tube-making machines, and pertains to a machine in which a rotating cylinder, an apron, and a separate mandrel or mandrels are used, all of which will be fully described herein-after and particularly referred to in the claims.

15 The object of my invention is to produce a cheap machine in which tubes for fire-crackers, fireworks, mailing-tubes, &c., can be rapidly produced and which is adapted to form long, short, large, and small tubes, the 20 capacity of the machine being limited only to the speed of the operator in feeding the tube-mandrels thereto.

Referring now to the drawings, Figure 1 is a perspective view of a machine embodying 25 my invention, a part of the framework being shown in section. Fig. 2 is a vertical transverse sectional view of the machine. Fig. 3 is a side elevation of the same. Fig. 4 is a top plan view. Fig. 5 is a detached perspective 30 view of the tube-mandrel.

In the drawings, A indicates a base from which project the standards B, the said standards being connected by means of the horizontal beams C and D, forming in top plan 35 view a rectangular frame, as shown. Journaled upon the side beams C is a roller E, which is covered with any rough surface, such as wire-netting or coarse canvas, but preferably of corrugated rubber, as here shown. 40 This roller or cylinder will be made of any desired length or diameter, according to the largest-sized tube it is intended to produce. Coacting with this roller or cylinder E is a flexible apron F, which will be formed of a rough material, such as that which covers the roller E, and the forward end of this apron is suitably connected with a suitable cross-bar G. This cross-bar G is provided at its 45 ends with laterally-projecting ears or plates 50 a, having longitudinal slots b, and passing through these slots b are the clamping-screws c, which are screwed into the U-shaped

brackets d, whereby this supporting-bar for the upper or forward end of the apron is adjustable to and from the roller. The opposite 55 and lower exit end of this apron is provided with a spring tension device, preferably of coiled springs I, which have one end connected with an adjustable bolt J and their opposite ends connected with a bar K, attached 60 to the lower and exit end of the apron. It will be readily understood, however, that other forms of springs and means for adjusting their tension can be provided and accomplish the same result. By means of this arrangement the apron is held to coöperate with 65 the roller with any desired amount of tension.

While the apron may be held in contact with the roller, I prefer to support the apron out of contact with the roller for the purpose 70 of preventing friction between the roller and the apron. This is accomplished by providing the apron with a plurality of transverse slats e, having their ends held in any desired manner for preventing the apron from coming in contact with the roller. The means 75 here shown for accomplishing this consists of the lacing f, which is connected, respectively, with the ends of the slats and with the framework of the machine and by means of which 80 the apron is held adjacent to but out of contact with the roller.

By reference to Fig. 2 it will be seen that for about one-fourth of the diameter of the roller the apron is on a parallel curve therewith and its upper end is held away from the roller, which forms an inclined or wedge-shaped space L for the reception of the tube-mandrel m, as clearly illustrated in said Fig. 2. The lower and exit end of the apron is 90 preferably formed on an approximately-horizontal plane, as shown at N, and situated below the exit end of this apron are inwardly-projecting mandrel and tube catching arms g, which extend inward under the exit end of 95 the apron from the inner edge of the tube-receiving shelf h, the outer edge of the shelf h having the stops or projections i for preventing the mandrel and the formed tube from rolling therefrom and for supporting it 100 until it is removed by the stripping boy or operator.

Projecting outward from the bar which is attached to the upper end of the apron is a

supporting-shelf *P*, preferably formed of a plurality of rods, as shown, and upon which the mandrel *m* is placed and supported while the operator places the edge of the sheet *n* therein.

Projecting across and out of contact with the roller, just above the inlet or upper end of the apron, is a guard *r*, for a purpose which will be presently described.

10. By reference to Fig. 5 it will be noted that the mandrel is formed of heavy tubular metal and provided with a longitudinal slot *s*, into which the edge of the paper from which the tube is to be formed is inserted, and then the 15 paper is bent or creased slightly by the operator, as shown in Fig. 2.

In operation there will be as many mandrels as will be desired, and the feeding operator will place one edge of the sheet in the 20 slot of the mandrel and bend or crease it slightly outward, as illustrated, and then drop the mandrel between the upper end of the apron and the roller, the opposite edge of the paper being gummed, and rest the projecting 25 portion of the sheet against the guard *r*. The mandrel being dropped into the V-shaped space between the inlet end of the apron and the roller, it is caught and revolved and carried around through between the roller and the 30 apron, thus wrapping the paper therearound and delivering the mandrel to the shelf *h* with the tube formed thereon. The stripping boy will then remove the tube therefrom and pass the mandrel again to the feeding 35 operator.

From this description it will be seen that there may be one, two, or more of the mandrels passing through between the roller and the apron, according to the speed with which 40 an operator can supply the mandrels.

In order to have the machine operate, it is necessary that a powerful pressure be obtained upon the mandrel, and therefore it is necessary to provide a cylinder having practically a rigid friction-surface. The rubber which is placed upon the cylinder and upon the paper is of that character which is only sufficiently yielding to provide a friction-surface, while at the same time it provides practically a rigid surface capable of receiving a heavy pressure, which is necessary to cause the mandrel to revolve and to roll the paper tube thereon.

By forming the mandrel of a tube instead 55 of a solid rod I reduce the friction upon the tube and am enabled to remove the tube from the mandrel without cutting it. This is also assisted from the fact that the edge of the sheet which is placed in the slot of the 60 tube is accessible to the fingers of the operator for drawing the tube therefrom.

I find that by the use of a machine as herein described, which is cheap to construct, I can greatly increase the output of tubes for

mailing-tubes, fireworks, or other purposes 65 over the usual method or machine for constructing similar tubes and that the machine is adapted to form large, small, long, or short tubes, as may be required, being limited in length only by the length of the roller *E* and 70 the width of the apron coacting therewith. It will also be noted that I am enabled to regulate the tension of the apron according to the thickness of the sheet from which the tube is being formed.

Having thus described my invention, what I claim, and desire to secure by Letters Patent, is—

1. A tube-rolling machine comprising a roller having practically a rigid friction-surface, a segmental concaved surface extending partially around and adapted to receive between it and the roller a mandrel and rotate the latter under pressure for forming a tube, and a mandrel upon which the tube is 80 rolled, substantially as described.

2. A tube-rolling machine comprising a perfectly-cylindrical roller having practically a rigid friction-surface, a segmental concaved surface coacting therewith and adapted to receive a mandrel between it and the roller and to rotate the mandrel under pressure to form a tube, and a mandrel upon which the tube is rolled as it passes between the concaved surface and the roller, substantially as 95 described.

3. A machine for forming tubes comprising a roller having a practically-rigid friction-surface, an apron supported adjacent thereto and provided on its outer side with transverse slats, a holding means between the slats, and the machine-frame for holding the apron out of contact with the roller, a yielding member for holding the apron under tension, and a mandrel upon which the tube is formed, 105 substantially as described.

4. A machine for forming tubes comprising a roller having a practically-rigid friction-surface, an apron adapted to coact therewith, a mandrel upon which the tube is formed, and 110 a guard extending across the roller at a point above the inlet end of the apron for the purpose described.

5. A machine for forming tubes comprising a roller having a practically-rigid friction-surface, an apron supported at its upper and lower ends, the apron having between its ends transversely-extending slats, and lacings connecting the slats and the frame of the machine for supporting the apron out of contact 120 with the roller, substantially as described.

In testimony whereof I have hereunto set my hand in the presence of two subscribing witnesses.
